(57) **CLAIM**

The ornamental design for automobile tire tread, as shown and described.

DESCRIPTION

FIG. 1 is a front view of an automobile tire tread, showing the new design, a top plan view thereof and a bottom plan view thereof appearing the same as the front view; FIG. 2 is a rear view of the automobile tire tread; FIG. 3 is a right side view of the automobile tire tread; FIG. 4 is a left side view of the automobile tire tread; FIG. 5 is a fragmentary front view, showing in enlargement the portion of 5—5 in FIG. 1; FIG. 6 is a cross-sectional view, taken along lines 6—6 and in the direction of arrows in FIG. 5; and, FIG. 7 is a perspective view of the automobile tire tread. The broken line showing of a tire sidewall and inner bead, and the peripheral boundary between the tire tread and sidewall, indicates environmental structure only and forms no part of the claimed design.
